CLAIM

The ornamental design for a cover for scanner, as shown and described.

DESCRIPTION

FIG. 1 is a top, front, and right side perspective view of a cover for scanner showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front, and left side perspective view showing the cover for scanner in an opened configuration;

FIG. 9 is a bottom, front, and right side perspective view of FIG. 8; and,

FIG. 10 is a left side elevation view of FIG. 8.

The broken lines depict portions of a scanner showing the environment that form no part of the claimed design.
